RECOVERY OF TAR ACIDS OR PHENOLS FROM TARS OR TAR OILS

Vittorio Molinari, Milan, Italy, assignor to Bakedite Corporation, New York, N. Y., a corporation of Delaware

No Drawing. Application August 19, 1933,
Serial No. 685,853

4 Claims. (Cl. 260—627)

This invention relates to the recovery of tar acids or phenols from tars or tar oils such as coal tar, shale tar, lignite tar, wood tar, or their oils, tar oil obtained from the low temperature distillation of coal, mineral oil which contains tar acid or oil from petroleum cracking processes, etc.

It is known to extract phenols, i. e., tar acids, from tar oils by the use of caustics but this is relatively costly due, among other factors, to the necessity of using and having to recover a large amount of the relatively expensive caustic, some of which is lost in every cycle and must be replaced. Other methods of recovering phenols involve the addition of organic salt solutions to the tar oil. Some of these methods afford only a partial extraction of the phenols while others produce phenols which are quite impure, the phenols frequently being contaminated with up to 35 or 40 per cent neutral oil.

The method of extracting tar acids of the present invention seeks to overcome the objections to the prior art by using relatively inexpensive reagents and thereby obtaining a substantially complete extraction of the acids or phenols in substantially pure condition in a minimum number of steps. Pyridine or other organic base compounds present in the tar oils can also be separated by this process from neutral oil and phenols.

According to the present invention tar oil which contains neutral oil (hydrocarbon derivatives of benzol and naphthalene), tar acids and pyridine base compounds, is treated with a material made up of a solvent for the neutral oil, a solvent for the tar acids, an ingredient to form a salt with the pyridine and other base compounds and preferably another ingredient or repellent to prevent the neutral oil and its solvent from dissolving in the tar acid or tar acid solvent. The solvents are furthermore so chosen that they are immiscible in order that the solutions formed will divide into two layers which can readily be separated. In addition the solvents are of a type so that they can later be separated from their solutes and returned for the separation of further amounts of tar acids.

By the conjoint addition of solvents for tar acids and for neutral oil to crude tar oils, the process of tar acid extraction is materially simplified while at the same time the purity of the acid fraction separated is greatly improved, particularly if the solvents are of an immiscible character. If either solvent is added alone, the fraction of either tar acid or neutral oil obtained is diluted

to such an extent with the other fraction that a subsequent treatment with another solvent becomes necessary; this dual treatment can be substantially avoided by the present process and a tar acid fraction of improved purity obtained as well. The further inclusion of a salt-forming ingredient incorporates another step of purification taking place simultaneously with the tar acid extraction while in addition the extraction is benefited through the formation of a tar acid solvent. Purification of the tar acid fraction is still further improved with the addition of an agent acting as a repellent for the neutral oil; because of the action of the solvents in causing a separation, the repellent is afforded an opportunity to make the separation more complete.

A solvent for the neutral oil complying with the purposes of this invention is one which dissolves substantially no phenols or at least dissolves less phenols than the neutral oil and which has a characteristic differing from that of the neutral oil to permit their separation later in the process. Solvents found suitable are aliphatic hydrocarbons such as mineral oil, petroleum kerosene, gasoline, etc., or their derivatives for instance halogens, tetrachlor ethane, ethylene dichloride, trichlorethylene, trichlorethane, etc., preferably so chosen as to have a boiling point different from the boiling point of the neutral oil in order that they may be separated by simple distillation if desired. The amount of solvent used is such that it easily dissolves all of the neutral oil.

A solvent for the tar acids is one which is insoluble in the neutral oil or the neutral oil solvent, and has a characteristic enabling it to be separated from the phenols later in the process whereby the phenols are obtained and the solvent may be returned to the process. A suitable solvent is a concentrated solution of a salt of an organic base in water or other appropriate liquid. Such a salt of an organic base can be formed by the interaction of an acid with one or more of the organic bases which are present in the tar oils, as for instance a salt formed by the interaction of an inorganic acid, such as sulphuric, nitric, hydrochloric, or an organic acid such as acetic or formic, with the organic bases such as pyridine, picoline, lutidine, quinoline, etc. The said solution should have the property of dissolving large amounts of the tar acids and is therefore preferably used in concentrated form since the concentrated solution dissolves tar acids while a weak solution does not. A 70 per cent or higher concentration works satisfactorily but any

concentration that extracts and holds the phenols can be used. Sufficient amount of this solvent is used to dissolve substantially all of the tar acids, control tests being run in a laboratory prior to 5 commercial use with any given tar oil to determine the amount, which is usually from about 20 to 40 per cent by volume of the tar oil treated.

Another ingredient of the material added to the 10 tar oil is a free acid which reacts with organic bases to form salts. This acid addition is for the removal of organic bases present in the tar oil, and the salts thus formed become part of the solvent for the tar acids. The acids may be those 15 previously mentioned, namely inorganic acids such as sulphuric, hydrochloric, nitric, etc., or strong organic acids such as acetic, formic, etc.

The phenols, even though they be dissolved in a solvent which does not of itself dissolve neutral oil, carry some of the neutral oil into the 20 solution. The neutral oil will contaminate the phenols if not separated from them. To accomplish this separation, the material which is used to treat the tar oils includes a repellent for the neutral oil. The repellent should be soluble in 25 the phenol and repel the neutral oil so that when absorbed into the combination of phenol and organic base salt that is formed, it forces out the neutral oil. Suitable repellants are found to be organic or inorganic salts of alkaline or alkaline earth bases such as sodium benzene sulphonates, sodium naphthalene sulphonates, sodium sulphate or perchlorate, calcium chloride, etc. All of these are soluble in water so that they may 30 be separated from the tar acids later in the process.

In carrying out the process, the material made up of the previously mentioned ingredients, is added to the tar oil and thoroughly mixed. The mixture is then permitted to stand whereupon 40 two layers are formed. The upper layer contains the neutral oil and the aliphatic hydrocarbon solvent while the bottom layer contains the phenols dissolved in the organic base salt solution and also the repellent. The top layer is 45 withdrawn from the separating vessel and subjected to a simple distillation whereby the aliphatic hydrocarbon solvent is separated from the neutral oil and may be returned to the cycle, being used to treat fresh quantities of crude tar oil. To extract the last traces of tar acids from 50 the mixture of neutral oil and neutral oil solvent, this mixture can be washed with fresh tar acid solvent which may later be used in the first step of the process.

The bottom layer containing the phenols and 55 organic base salts is diluted with water (usually less than 50% of the original volume) whereupon the phenols rise to the top of the diluted solution and the organic base salts form the bottom layer together with the small amount of repellent. The phenols may then be withdrawn as the final product of the process and may, if desired, be washed with a small amount of acid to remove traces of bases. This acid may 60 thereafter be used as an ingredient for preparing the tar acid solvent in the first step of the process. The dilute water solution of organic base salts and repellent may easily be concentrated by evaporation and returned to the cycle as the ingredient for separating phenols from fresh 65 charges of tar oils. The pyridine or other base salts which are thus formed in every cycle may be treated with strong alkali to liberate and thereby recover the bases from the salts.

The only chemical which need be supplied to

the process is a sufficient quantity of free acid to react with the organic bases. As previously indicated, there is a wide choice of acids, the least expensive of which is probably sulphuric acid. If the organic bases are not objectionable 5 in the neutral oil, the free acid may be omitted since the pyridine or other bases will be separated from the phenols in the first separation, that is, they will remain dissolved in the neutral oil and neutral oil solvent. By the use of the 10 free acid, the organic bases are first dissolved with and then recovered from the tar acid solvent as previously indicated.

If an extremely pure tar acid is desired, the 15 tar acid-organic salt solution may be washed before the water dilution, with fresh aliphatic hydrocarbon. This washing removes all traces of neutral oil. The last traces of the aliphatic hydrocarbon may be removed by gentle heating, preferably under vacuum, before the water dilution. With such a washing, the phenols which are obtained as final products of the process are approximately 98-99 per cent pure.

From the previous description, the principle of the invention will readily be understood but for 25 complete disclosure the following illustrative examples are given.

Example 1

One liter of middle coal tar oil having a distillation range between 160 and 260° C. with a content of 30 per cent of tar acid and 4 per cent pyridine or other coal tar bases, is mixed with .75 liter of an aliphatic hydrocarbon distilling between 120 and 160° C. (containing as identified oils principally octane, nonane, or mixtures), 250 30 cc. of a concentrated solution of sulfates of pyridine bases, 3 per cent free sulphuric acid and 0.5 per cent sodium benzene sulfonate.

Upon standing approximately 600 cc. of tar acid extracting solution containing the phenols 40 and the pyridine bases will be obtained as the bottom layer. The solution is washed three times with 250 cc. of the same quality of aliphatic hydrocarbons which will be used for the next extraction.

The washed solution is heated to about 45-50° C. under vacuum to eliminate traces of aliphatic hydrocarbons and is then diluted with water to 900 cc. 275 cc. of tar acids separate in the upper layer upon standing, which after washing with dilute sulphuric acid, shows a purity of 98-99 per cent. The original extracted neutral oil with the aliphatic hydrocarbons is washed with fresh tar acid extracting solution two or three times to extract traces of phenols. The solution will 55 be used for the next extraction and by this there is no loss in phenols.

The aliphatic hydrocarbon can be reclaimed from the neutral oil by distillation in vacuum and used again.

Example 2

One liter of low temperature distillation coal tar oil with a distillation range between 175 and 250° C. with a content of 35 per cent of tar acid 65 and 3 per cent of pyridine or other coal tar bases is mixed with 0.60 liter of aliphatic hydrocarbon distilling between 120 and 170° C. (containing as identified oils principally octane, nonane, or decane or mixtures) 300 cc. of a concentrated 70 solution containing triethanolamine sulphate, 2 per cent of sulphuric acid (free) and 0.5 per cent of sodium sulphate.

The treatment in Example 1 is followed and phenols with the same purity and in proportional 75

amount are obtained. The tar acid extracting solution can be reclaimed by concentration and used again for another extraction. The aliphatic hydrocarbons can be reclaimed from the neutral oil by distillation in vacuum.

Example 3

One liter of lignite tar oil having a distillation range between 180 and 250° C. and a content of 10 38 per cent of tar acid and 2 per cent of pyridine or other coal tar bases is mixed with 0.50 liter of kerosene distilling above 260° C., 350 cc. of a concentrated solution containing pyridine bases chloride, 1.5 per cent hydrochloric acid (free) 15 and 1 per cent calcium chloride.

The treatment in Example 1 is followed and phenols with the same purity and in proportional amount are obtained. The tar acid extracting solution can be reclaimed by concentration and used again for a new operation. The neutral oil can be separated from the kerosene by distillation in vacuum in a still with a rectification column; the neutral oil distills over and the kerosene remains as a residue in the still. It can 25 be used again for a new operation.

The amounts, proportions, and kind of the various materials in the fluid extracting solution may be varied within wide limits depending upon the quality of the tar or tar oil as determined 30 by a control laboratory.

If the tar oil contains more or less tar acid or neutral oil, or organic bases, the amount and characteristics of the solvents will be changed accordingly. The invention is not limited to the 35 quantity or quality of the salt of the organic base used, such as primary, secondary, etc., aliphatic or aromatic compounds, nor to the quality or quantity of the alkali or alkali earth salt used in the extracting solution, nor limited to the

quality or quantity of the free acid present in the extracting fluid.

I claim:

1. In a method of separating tar acids from crude tar oils including organic bases, tar acids 5 and neutral oils, the step which comprises treating a tar oil with a mixture including a free acid, a solvent for tar acids and a solvent for neutral oils, said solvents being substantially immiscible.

2. In a method of separating tar acids from 10 crude tar oils including tar acids and neutral oils, the step which comprises treating a tar oil with a mixture including a solvent for tar acids, a solvent for neutral oils and a repellent to decrease the solubility of the neutral oil in the combination of tar acid and tar acid solvent, said solvents being substantially immiscible.

3. In a method of separating tar acids from crude tar oils including organic bases, tar acids 15 and neutral oils, the step which comprises treating a tar oil with a mixture including a solvent for tar acids, a solvent for neutral oils and an ingredient to render the bases soluble in the tar acid solvent, said solvents being substantially immiscible in the presence of their solutes, and 20 separating the solvents with their respective solutes.

4. In a method of separating tar acids from crude tar oils including tar acids and neutral oils, the step which comprises treating a tar oil 25 with a mixture including a solvent for tar acids and a solvent for neutral oils, said solvents being separable in the presence of their solutes, separating the solvents with their respective solutes, washing the neutral oil solvent containing neutral oil with fresh tar acid solvent, and using this tar acid solvent to treat fresh quantities of tar oil.

VITTORIO MOLINARI.
